(57) **CLAIM**

I claim the ornamental design for an off-ground tent with arched ceiling, as shown and described.

DESCRIPTION

FIG. 1 is a perspective view of my new design of an off-ground tent with arched ceiling;

FIG. 2 is a front view of the design of FIG. 1;

FIG. 3 is a back view of the design of FIG. 1;

FIG. 4 is a left side view of the design of FIG. 1;

FIG. 5 is a right side view of the design of FIG. 1; and,
 FIG. 6 is a top view of the design of FIG. 1.

The broken lines shown represent environment only and form no part of the claimed design.

1 Claim, 6 Drawing Sheets
